UNITED STATES PATENT OFFICE.

JAMES S. PATTEN, OF BALTIMORE, MARYLAND.

RAIL-JOINT.

SPECIFICATION forming part of Letters Patent No. 662,809, dated November 27, 1900.

Application filed April 21, 1900. Serial No. 13,741. (No model.)

To all whom it may concern:

Be it known that I, JAMES S. PATTEN, residing at Baltimore, in the State of Maryland, have invented a new and useful Improvement 5 in Rail-Joints, of which the following is a specification.

My invention is an improvement in rail-joints; and it consists in certain novel constructions and combinations of parts, as will 10 be hereinafter described and claimed.

In the drawings, Figure 1 is a cross-sectional view of a rail provided with my invention with the joint fastened. Fig. 2 is a similar view showing the joint unfastened and 15 with the rail and clamping-section in position for operation to press the rail home to its seat in the clasp-section. Fig. 3 is a detail perspective view of the clamping-section, and Fig. 4 is a detail perspective view of the clasp- 20 section.

The rail-joint, as shown, comprises the chair and the bolt and nut by which the chair is held firmly to the rail. The chair, as shown, includes the clasp-section A and the clamping-section B. The clasp-section A is provided with the upright wing or fish-plate A', the inwardly-opening seat A², into which one edge of the rail-base may fit, the base-plate A³, on which the base of the rail may rest, 25 and the upturned portion A⁴ at the free edge of the base-plate A³ and opposite the seat A², as shown in Figs. 1, 2, and 4. The upturned portion A⁴ is provided on its inner side with the inclined face A⁵, which operates by a 30 wedging action to force the base of the rail firmly into the seat A² of the clasp-section in the operation of the device, as presently described. The outer extremity of the upturned portion A⁴ is extended laterally outward, producing a web A⁶ for engagement by a 35 returned hook-like portion on the clamping section B. The clamping-section B is formed with the fish-plate section B' and the base-section B², whose outer end is returned, 40 forming the hook B³ for engagement with the web A⁶ of the clasp-section, as shown in Figs. 1 and 2. When the clamping-section is engaged with the clasp-section, as shown in 45 Figs. 1 and 2, it will be seen that the hook B³ on the clamping-section does not project below the base-line of the clasp-section, but lies at its 50 under side in the same plane with that of the

clasp-section, so that the chair may rest flat upon any support, as may be desired. This result is accomplished by forming the clasp- 55 section with the upturned portion A⁴, which supports the web A⁶ in an elevated position, as shown. The base portion B² of the clamping-section is provided on its under side with a downwardly-extending fulcrum portion C, 60 which is arranged comparatively near the outer edge of the clamping-section, so it will bear upon the base of the rail near the outer edge thereof opposite to that which fits within the seat A² of the clasp-section A. The 65 purpose of this construction is to enable the operation of the chair-sections by the bolt and nut in such manner as to cause or effect the pressing of the rail firmly into place within the clasp-section, as will be understood 70 from Figs. 1 and 2.

In the operation of the described construction if the rail be fitted partially in the clasp-section, as shown in Fig. 2, the edge of its base at 1 (see Fig. 2) will bear upon the incline A⁵, and it is manifest that if pressure be exerted on the base of the rail above its edge 1 it will operate by reason of said incline A⁵ to force the base of the rail firmly into the seat A² of the clasp-section. To effect 80 this pressure, I form the clamping-section B to engage at its outer edge with the edge of the clasp-section beyond the incline A⁵ and also form the clamping-section with the downwardly-extending fulcrum portion 85 which bears upon the base of the rail and operates as the nuts are tightened to press the base of the rail into the seat A², so that the proper tightening of the nuts will adjust the chair-section B and the rail from the position 90 shown in Fig. 2 to that shown in Fig. 1, in which the rail is represented as firmly and snugly held by the chair-sections.

In adjusting the chair-section from the open position shown in Fig. 2 to the closed position 95 shown in Fig. 1 it will be seen that the hook B³ on the clamping-section B will slide laterally upon the web A⁶ of the clasp-section, so that the hook will be in full engagement with the web in the fastened position of the parts. 100

It will be seen that the chair-sections are so formed that they can be conveniently rolled and thus produced at the minimum cost ready for use.

Having thus described my invention, what I claim as new, and desire to secure by Letters Patent, is—

1. The combination in a rail-joint with the rail, of the chair composed of the clasp-section having an upright fish-plate, a laterally-opening seat for one edge of the rail, and a base-plate having, at its edge opposite said seat, an upturned portion having an incline upon which the base of the rail operates, and a laterally-projecting elevated web, and the clamping-section having a fish-plate and a base-plate provided at its outer edge with a hook to engage the web of the clasp-section, said base-plate of the clamping-section being provided on its under side with a downwardly-extending fulcrum portion arranged to bear upon the base of the rail and press the edge of the latter down upon the inclined surface of the base of the clasp-section, all substantially as and for the purposes set forth.

2. In a rail-joint, the chair composed of the clasp-section having a fish-plate, a laterally-opening seat for one edge of the rail-base, and a base-plate provided at its edge opposite said seat with an upturned portion having an inclined surface on its inner upper face against which the edge of the rail-base may

bear and provided with a laterally-projecting web beyond said inclined surface, and the clamping-section having a fish-plate and a base-plate provided on its under side near its outer edge with a depending projection to bear upon the base of the rail over the inclined surface of the base of the clasp-section and having at its outer edge a returned portion forming a hook adapted to engage over the web at the outer edge of the base of the clasp-section, substantially as set forth.

3. A chair for rail-joints comprising the clasp-section having a laterally-opening seat for the edge of the rail-base, and a base-plate provided near its free edge with an inclined surface adapted to operate by a wedging action upon the edge of the rail, and the clamping-section having a base-plate adapted at its outer edge to engage with that of the base of the clasp-section and provided on its under side with means by which to press upon the base of the rail and force the rail into the seat of the clasp-section, substantially as set forth.
